ILLUMINABLE CLOCK

Matthias A. Weisz, Long Beach, N. Y.

Application February 3, 1953, Serial No. 23,405

Term of patent 3½ years

(Cl. D42—7)

To all whom it may concern:

Be it known that I, Matthias A. Weisz, have invented a new, original, and ornamental Design for an Illuminable Clock, of which the following is a specification, reference being had to the accompanying drawing, forming a part hereof.

Figure 1 is a front elevation of the illuminable clock, showing my new design;

Fig. 2 is a rear elevation thereof;

Fig. 3 is a side elevation thereof; and

Fig. 4 is a top plan view thereof, partly in section for the purpose of better showing the configuration of the center disk element.

The dominant features of my design reside in the portions shown in full lines.

I claim:

The ornamental design for an illuminable clock, as shown and described.
